UNITED STATES PATENT OFFICE

HENRY PERCY HOWLETT, OF STOKE-ON-TRENT, ENGLAND, ASSIGNOR TO HERMAN C. KUPPER, INC., OF NEW YORK, N. Y., A CORPORATION OF NEW YORK

DESIGN FOR A PLATE OR SIMILAR ARTICLE

Application filed March 13, 1930, Serial No. 34,852, and in Great Britain December 16, 1929. Term of patent 7 years.

To all whom it may concern:

Be it known that I, HENRY PERCY HOWLETT, a subject of the King of Great Britain, residing at Stoke-on-Trent, county of Staffordshire, England, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

HENRY PERCY HOWLETT.
